UNITED STATES PATENT OFFICE.

MORITZ GROSS AND BERNHARD B. ZIPPERT, OF NEW YORK, N. Y.

DESIGN FOR A MUFF.

Specification forming part of Design No. 6,826, dated August 26, 1873; application filed June 28, 1873.

To all whom it may concern:

Be it known that we, MORITZ GROSS and BERNHARD B. ZIPPERT, both of the city, county, and State of New York, have invented a Design for Muffs, of which the following is a specification:

The nature of our design is fully represented in the drawings accompanying, to which reference is made, and in which—

Figure 1 represents the muff in perspective, turned so as to show a porte-monnaie in front. Fig. 2 represents a similar view, turned so as to show the arch of porte-monnaie-clasp, also head of animal, &c. Fig. 3 represents the muff turned over to show opposite portion.

A is a central portion of the muff, and is made of dark fur, and B represents a border of the muff, made of very light-colored fur. At C is a porte-monnaie or pocket, arranged with regard to the muff in such manner that its clasp C' extends laterally across, arching outward from the muff-clasp, made of any suitable material, and to this clasp C' are attached the covering

portions of pocket, marked D and E, usually made of leather, but other material will answer; and on the portion marked E we stamp, in gilt, a coat of arms, monogram, or other suitable device, as shown. The white border B is continued across the muff in stripe, so as to inclose the porte-monnaie, forming a border thereto, and indicated by the letters B¹ and B², and we usually finish one point of stripe B² with a head, as shown at F.

We prefer to make the central portion A of black fur and the border B of pure white fur, the leather of porte-monnaie of blue, and the clasp of brass or gilded metal, and the arms or monogram stamped in gilt.

What we claim as our invention is—

The design for a muff herein shown and described.

MORITZ GROSS.

BERNHARD B. ZIPPERT.
